CLAIM

The ornamental design for a unitary water ski rope handle and reel, as shown and described.

DESCRIPTION

FIG. 1 is a perspective view of a unitary water ski rope handle and reel showing my new design;

FIG. 2 is an end elevation of one end thereof, and the end elevation of the other end is a mirror image of FIG. 2; and

FIG. 3 is a side elevation thereof with one end portion being omitted for ease of illustration.

Each end of the water ski rope handle is identical to the other end and the design is symmetrical so that opposite sides are identical.
